UNITED STATES PATENT OFFICE.

GEORGE WALTER NORRAGE, OF CHICAGO, ILLINOIS, ASSIGNOR TO BENJAMIN ELECTRIC MANUFACTURING COMPANY, OF CHICAGO, ILLINOIS, A CORPORATION OF ILLINOIS.

ELECTRIC SIGNAL DEVICE.

1,186,123.

Specification of Letters Patent. Patented June 6, 1916.

Application filed May 9, 1914. Serial No. 337,493.

To all whom it may concern:

Be it known that I, GEORGE WALTER NORRAGE, a citizen of the United States, residing at Chicago, in the county of Cook and State of Illinois, have invented new and useful Improvements in Electric Signal Devices, of which the following is a full, clear, concise, and exact description, reference being had to the accompanying drawing, forming 10 a part of this specification.

My invention relates to electric signal devices, and specifically to the type of said devices known as buzzers.

One of the objects of my invention is to 15 provide an electric signal device of this type wherein the vibrating member also serves as a housing for the electromagnet.

A further object of my invention is to improve upon the details of construction of an 20 electromagnet signal device.

An electric signal device constructed in accordance with my invention is described, by way of example, in the following specification and shown in the accompanying 25 drawings. It is to be understood, however, that my invention may be embodied in signal devices of other types than that described and shown, and that changes may be made in the construction which I have 30 chosen and illustrated without exceeding the scope of the invention as defined in the appended claims.

In the drawings, Figure 1 shows a section of my device on the line 1—1 of Fig. 2; 35 Fig. 2 shows a section on the line 2—2 of Fig. 1; and Fig. 3 shows a view substantially similar to Fig. 2 of a modification of my device.

Referring now to the drawings and to the 40 modification of Figs. 1 and 2, the device comprises a base 10 having secured thereto an electromagnet 11, said magnet being secured, by means of its core 12 passing through an aperture in the base. The lead 45 wires 13 and 14 from said electromagnet are secured to binding posts 15 and 16 mounted on the base 10. A spring 17 also secured to the base by means of the core 12 of the electromagnet has secured thereto, by means of 50 rivets 18, a dished housing 19 of sheet metal. The operation of this modification is as follows:

The binding posts 15 and 16 are connected with an alternating current circuit, although 55 it is obvious that my invention is not lim-

ited to an alternating current device; the alternations of current in the electromagnet cause the housing 19 to vibrate and its edge adjacent the base 10 and on the opposite side from the rivets 18 to strike against the 60 base 10, thus producing a hammering or chattering noise, in addition to the buzzing or humming produced by the vibrations of the disk. In the modification of Fig. 3 the base 10^a has secured thereto by means of 65 rivets 18^a a dish-shaped sheet metal housing 19^a. The alternations of current in the electromagnet 11 cause the upper flat part of the housing to vibrate, this part being located so near the core 12 of the electromagnet that it strikes against it as it vibrates, thus producing a hammering noise in addition to the buzzing noise produced by the vibrations of the flat part.

It will be noted that the base 10 is dished 75 on the lower side and hence acts as a resonator when the dished housing 19 strikes it.

Having thus described my invention what I claim as new and desire to secure by Letters Patent is—

1. An electric signal device comprising a support, a bodily movable housing resiliently mounted with respect to said support and means including an electromagnet within said housing for moving said housing 85 into and out of contact with a part of said device.

2. An electric signal device comprising a support, a movable metallic part, and means including spring means for mounting said part on said support, and also including an electromagnet housed by said metallic part for moving said movable part into and out of contact with a part of said device.

3. An electric signal device comprising a base, a housing of sheet metal movably and resiliently mounted on said base in a position to be moved into and out of contact therewith, and an electromagnet mounted on said base and substantially enclosed by said housing 100 for moving said housing.

4. An electric signal device comprising a dished base, a housing of sheet metal movably and resiliently mounted on said base in a position to be moved into and out of contact therewith, and an electromagnet mounted on said base and substantially 105 enclosed by said housing for moving said housing.

5. An electric signal device comprising a 110

support, an electromagnet mounted thereon, a metallic housing for said electromagnet, and spring means mounted on said support for supporting said housing in a position to be actuated by said magnet and in a position to be moved into and out of contact with a part of said device.

6. An electric signal device comprising a base, an integral dished housing of sheet metal movably and resiliently supported on said base in a position to be moved into and out of contact therewith, and an electromagnet mounted on said base and substantially inclosed by said housing for moving said housing.

7. An electric signal device comprising a base, a spring member mounted thereon, an electromagnet also mounted thereon, the core of said magnet extending through said spring member and being secured to said

base, and the metallic housing for said electromagnet movably supported by said spring member in a position to be moved into and out of contact with a part of said device and in a position to be actuated by 25 said magnet.

8. An electric signal device comprising a support, a dished part movably and resiliently mounted on said support, and means including an electromagnet housed by said 30 dished part for moving it into and out of contact with a part of said device.

In witness whereof, I have hereunto subscribed my name in the presence of two witnesses.

GEORGE WALTER NORGATE.
